UNITED STATES PATENT OFFICE.

WILLIAM A. SCHLEICHER, OF CLEVELAND, OHIO.

HAME AND TRACE CONNECTOR.

1,118,448.

Specification of Letters Patent. Patented Nov. 24, 1914.

Application filed June 5, 1914. Serial No. 843,167.

To all whom it may concern:

Be it known that I, WILLIAM A. SCHLEICHER, a citizen of the United States, residing at Cleveland, in the county of 5 Cuyahoga and State of Ohio, have invented a new and useful Improvement in Hame and Trace Connectors, of which the following is a full, clear, and exact description, reference being had to the accompanying 10 drawings, forming part of this specification, in which—

Figure 1 is a side view showing my improved hame and trace connector applied to a portion of a bolt hame; and Fig. 2 is a 15 section on the line II—II of Fig. 1.

My invention has relation to hame and trace connectors for harness, and is designed to provide a simple and efficient form of connector which gives a free, universal 20 connection between the trace and hame; which can be readily constructed and assembled, and in which the parts are prevented from binding when assembled.

Referring to the accompanying drawings, 25 the numeral 2 designates a portion of a bolt hame having the bolts 3 formed with the usual projecting portions 4, in which the vertical pivot bolt 5 for the connector is seated and secured.

30 6 designates a portion of a trace whose end is attached in the usual manner to the D-member 7.

8 designates a metallic clip formed from a single piece of metal bent over upon 35 itself to form the parallel inner and outer jaws 9, between which the eye 10 of the D-member is seated. The central portion of the blank forming the clip is bent to 40 form a partially cylindrical barrel 11, this barrel extending through about three-quarters of a circumference. This barrel forms the seat for the usual loose sleeve or roller 12, which turns on the bolt 5. The eye 10 of the D-member has a loose bearing on 45 a bushing 13, through which extends the rivet 14, which connects the D-member to the clip. One of the jaws 9 has an opening large enough to receive the bushing 13;

but the bushing terminates at its other end at the inner face of the other jaw 9, the opening in which is only large enough to receive the rivet 14. When the end portion 15 of the rivet is headed, the heading action is taken by the end of the bushing. This prevents any tendency to bind the two jaws 55 against the eye, and thus prevent freedom of its movement. It also tightens the rivet in the bushing so that the bearing of the eye 10 of the D-member is transferred to the outer surface of the bushing. This permits the bushing to be made of relatively hard metal, while the rivet may be made of soft metal. This manner of seating the bushing also prevents the jaws 9 from being clamped together by the riveting sufficiently 60 to bind the barrel or roller 12. The latter is thus perfectly free to turn in the barrel portion of the clip. The form of this barrel portion is such as to prevent any back and forth movement of the clip relatively to 70 the bolt 5.

The above described construction is an exceedingly simple and convenient one, and forms an admirable device for the purpose.

I claim:

1. A hame and trace connector comprising a clip having an approximately cylindrical barrel portion, a sleeve or roller seated and confined within said barrel portion, a bolt extending through the sleeve or 80 roller and connecting the clip to the hame, said clip having parallel jaw members, a D-member having an eye extending between the jaw members, and a pivot connection between the D-member and the clip, said 85 pivot connection having stop means for preventing binding of said jaws on either the D-member or said barrel portion, substantially as described.

2. A hame and trace connection comprising a clip shaped to form an approximately cylindrical vertical barrel portion with projecting substantially parallel jaw portions, a sleeve or roller seated and confined within said barrel portion, a D-mem- 90 ber having an eye extending between said 95

jaw portions, a bushing extending through one of the jaw portions and through said eye and terminating at its other end inside of the other jaw member, and a rivet extending through said bushing and both jaw members, said bushing forming a bearing for the eye of the D-member and also acting to prevent binding of the jaw portions on the D-member and of the barrel portion of

the clip upon the sleeve or roller, substantially as described.

In testimony whereof, I have hereunto set my hand.

WILLIAM A. SCHLEICHER.

Witnesses:

FRED J. AHRENS,

DANZIE W. GARRINGTON.
